CLAIM

The ornamental design for a can, as shown and described.

DESCRIPTION

FIG. 1 is a top perspective view of a can showing our new design;

FIG. 2 is a top perspective view thereof;

FIG. 3 is an enlarged top view thereof;

FIG. 4 is an enlarged bottom view thereof; and,

FIG. 5 is a side view thereof.

Broken lines in FIGS. 1-5 depict portions of the can that form no part of the claimed design. The can includes a symbolic break along its length drawn in dot-dash-dot broken lines. The dot-dash-dot broken break lines and the area between the break lines forms no part of the claimed design.
